COMBINED CLEANER AND DRIER

Carroll M. Gantz, North Canton, Ohio, assignor to The Hoover Company, North Canton, Ohio, a corporation of Ohio

Filed June 16, 1959, Ser. No. 56,380

Term of patent 14 years

(Cl. D9—2)

Figure 1 is a side view of a combined cleaner and drier showing my new design, and the opposite side is substantially the same as that shown;

The dominant features of my design reside in the portions shown in full lines.

I claim:

The ornamental design for a combined cleaner and drier, substantially as shown and described.
